Inventor
Joseph René Ayotte.

By: Forée Bain Phinkle
Atty.

Patented Dec. 12, 1922.

UNITED STATES PATENT OFFICE.

JOSEPH RENÉ AYOTTE, OF CHICAGO, ILLINOIS.

WRENCH.

Application filed December 2, 1921. Serial No. 519,332.

To all whom it may concern:

Be it known that I, JOSEPH RENÉ AYOTTE, a subject of the King of Great Britain, residing at Chicago, in the county of Cook 5 and State of Illinois, have invented certain new and useful Improvements in Wrenches, of which the following is a specification.

This invention relates to improvements in wrenches.

10 One of the objects of the invention is to improve the detailed construction and to simplify and reduce the cost of devices of the character of wrench described in my co-pending application Serial No. 541,162; filed 15 November 10, 1921.

Other objects and advantages of the invention will readily appear from a consideration of the following description when taken in conjunction with the drawings,

20 wherein:—

Fig. 1 is a central longitudinal section of the body of the wrench.

Fig. 2 is a similar view of the handle for rigid attachment to the internal rotatable

25 shaft.

Fig. 3 is a similar view of an attachment to the body part shown in Fig. 1.

Fig. 4 is a bottom end view of the body shown in Fig. 1, and of the handle shown in

30 Fig. 2.

Fig. 5 is a central vertical section of a clutch holding member.

Fig. 6 is an end view of the same.

In all the views the same reference characters are employed to indicate similar parts.

In the illustrated device 10 is a non-rotatable, tubular, straight jacket having a perforate closure 11 with a shoulder 12 against 40 which the tube 10 abuts. The closure 11 may be fixed to the jacket 10 or rotatable with respect thereto. A central shaft, preferably a rod, 13, passes thru the closure 11 and is provided with an angular head 14 to receive 45 a clutch member 15. A cooperating clutch member 16 is attached to the other end of the shaft, or rod 13, by a pin 17 and rotates with the rod, and with respect to the jacket or tube 10. Clutch member 16 is also provided with a shoulder 18, so that when the clutch members 15 and 16 are secured to the respective ends of the rod, the latter is thereby confined within the jacket 10.

The general form and arrangement of the 55 clutch members are similar to those shown in my aforesaid copending application, in

which a holding device 19 is secured inside of the clutch member 16 to the rod 13 by a screw 20. The clutch members 15 and 16 are cooperative, that is to say, the clutch member 16 engages the clutch member 15, as more clearly shown in Fig. 3. Fig. 3 shows an angular non-rotatable jacket 21 providing a notch 22 for engagement with an axial rib 23 on the member 10 to prevent the attachment 21 from rotating with respect to the member 10. The enlarged part 24 of the member 21 may be slipped over the lower end of the tube 10, and the rib 23 is received in the notch 22; at the same time the clutch member 16 will engage the clutch member 15 within the part 24, and thereby clutch member 15 and the other end of the member 21 is rotatable when the shaft or rod 13 is rotated. In like manner the clutch member 16 at the other end of the member 21 is rotatable when the rod 13 is rotated. The clutch member 16 of the attachment 21 in Fig. 3 will engage the clutch member 15 on the upper end of the structure shown in Fig. 1, and member 16 of the handle 27 may engage member 15 of the attachment 21 to rotate shaft 13, or the member 15 of the attachment 21 may engage clutch member 16 of Fig. 1 and the part 24 will engage jacket 85 10. The holding device 19 is provided with a snap ring 25 which engages the notch 26 and yieldingly holds the clutch member 15 within the clutch member 16. The inner surface of the clutch member 16 is angular 90 corresponding with the angular outer surface of the clutch member 15 so that the two may be rotated together.

The two clutch members 15 and 16 of the device shown in Fig. 3 are rotatably connected by a universal joint 26.

The handle 27 is for rigid connection with the clutch member 15 on the structure shown in Fig. 1 or in Fig. 3. The handle is transversely perforated for the rod 28 and a plunger 29 is yieldingly held against the inner surface of the rod 28 by the open helical spring 30. A screw 31 permits limited axial movement of the plunger 29 to frictionally hold the rod 28 in place with respect to the handle 27.

A socket 32 is a part of the clutch member 15, more clearly shown in Fig. 3, and may be used for rotating nuts having angular surfaces, such as hexagon or square screw threaded nuts, cap screws, bolts, and the like.

While parts of the structure herein shown

and described resemble parts of the structure disclosed in my prior application, in which they are specifically claimed therein, there are other features in the present invention cooperating with said devices which form the subject matter for the appended claims.

Having described my invention what I claim as new and desire to secure by Letters Patent, is:

- 10 1. A wrench comprising a non-rotatable tube; a perforate closure at one end thereof; an axially fixed rotatable shaft extending thru said tube and closure, confined within the tube, and a clutch member on the shaft at each of its ends whereby to confine the shaft within the tube.
- 15 2. A wrench comprising a non-rotatable tube; a perforate closure at one end thereof; an axially fixed rotatable shaft extending thru the tube and closure, confined within the tube and a pair of cooperating clutch members secured to the shaft one at each of its ends to confine the shaft within the tube.
- 20 25 3. A wrench comprising a non-rotatable

tube; a perforate closure at one end; an axially fixed rotatable shaft extending thru said tube and closure confined within the tube; a clutch member secured to the shaft at each of its ends to confine the shaft within the tube and a separable handle providing an integral clutch member arranged for rigid attachment with one end of said shaft.

4. A wrench comprising a non-rotatable tubular jacket; an axially fixed rod rotatable within the jacket; a clutch member of a cooperating pair of clutch members, fixed to each end of the rod; a separable angular jacket, attachable to the tubular jacket by a slip joint connection to prevent relative rotation of the parts; a clutch member at each end of the angular jacket for engagement with each end of said rod; a rotatable element therein connecting said clutch members and means to prevent relative rotation of said jacket.

In testimony whereof I hereunto subscribed my name:

JOSEPH RENE AYOTTE.
